UNITED STATES PATENT OFFICE.

OSWALD LORENZ, OF CORONA, AND HANS WEIDE, OF BROOKLYN, NEW YORK.

BAG AND SIMILAR FASTENER.

1,118,028.

Specification of Letters Patent. Patented Nov. 24, 1914.

Application filed June 30, 1913. Serial No. 776,533.

To all whom it may concern:

Be it known that we, OSWALD LORENZ and HANS WEIDE, citizens of the United States, residing at Corona and Brooklyn, respectively, counties of Queens and Kings, respectively, and State of New York, have invented certain new and useful Improvements in Bag and Similar Fasteners, fully described and represented in the following specification and the accompanying drawings, forming a part of the same.

This invention relates to certain improvements in devices for preventing the accidental opening of locks, latches, such as used to hold hand and other bags closed, the valves employed in gas lighting fixtures, and in other constructions including a movable part or member which is manually operated to move it from locking or unlocking or opening or closing position.

It is the object of the invention to provide a construction by which the movable member is operated to cause it to assume the desired position by means which are normally held out of operative relation with the member and which must first be brought into operative relation therewith before the member can be moved by such means to unlatching position, or in case of a valve, before the valve can be turned to open it, whereby accidental movement of the member is prevented.

It is a further object of the invention to provide such a construction in which the means employed for operating the member will be automatically returned and held in non-operative position with relation to the member after the member has been operated to move it to closed position, so that the member cannot again be moved until the operating means has been moved into proper relation therewith.

Generally the invention consists in providing an actuator which co-operates with the member to be moved, as for instance, the latch of a bag or the like, or the valve of a gas fixture, by which the latch or valve is operated to open and close the same, this actuator being normally held out of operative position with respect to the latch or valve and requiring a movement to be given it to bring it into such operative relation before it can be caused to give its actuating movement to the latch or valve. This actuator, furthermore, is so constructed, as by

seating it against a spring, that when it has been operated to close the latch or valve it is automatically returned to its non-operative position and cannot again be operated to open the latch or valve until it has been given a movement to bring it in operative relation therewith.

For a full understanding of the invention reference may be had to the accompanying drawings, in which is illustrated two constructions embodying the invention, the constructions chosen being a latch mechanism for use with hand bags and the like, and a gas lighting fixture. It will be understood, however, that the invention is capable of use in many other relations.

Referring now to the drawings, Figure 1 is a side elevation of a bag frame partly broken away showing the latch construction employed for holding the two parts of the frame closed and the improved actuator for operating the latch. Fig. 2 is a plan view of the construction shown in Fig. 1. Figs. 3 and 4 are cross sections taken respectively on the lines 3-3 and 4-4 of Fig. 1. Figs. 5 and 6 are views partly in section taken on the line 5-5 of Fig. 1 showing respectively the latch mechanism in closed and open position. Fig. 7 is a side elevation partly in section of a gas lighting fixture showing the valve and the improved actuator for operating the same, and Fig. 8 is a cross section taken on the line 8-8 of Fig. 7.

Referring now to Figs. 1 to 6 inclusive, 1 and 2 indicate the two parts of the frame usually employed in hand bags to which the leather of the bag is attached, the stationary member of the latch being secured to one of these frames, as 2, and the movable member being mounted on the other frame 1.

The particular form of latch construction employed may be widely varied. Preferably, however, the latch construction will be such that the parts of the bag frame will be prevented from opening until after the actuator for operating the latch has been given its operating movement, in other words, so that the latch cannot be operated except by operating the actuator. In the particular construction illustrated, the stationary member of the latch comprises a U shape plate 4, suitably secured on the frame 2 having inwardly extending legs 5, 6, the leg 6 being somewhat longer than the leg 5. These legs are each provided at points intermediate

their ends with apertures 7. Coöperating with the plate 4 of the latch is the movable member 8 which is secured on the frame 1. The particular construction of the movable member may be somewhat varied. As illustrated, it comprises a thin disk or plate having a collar or hub 10 which fits over a stud or projection 11 on a supporting plate 12 suitably secured on the bag frame, although if desired the stud could be formed on the frame 1 itself, the plate being freely rotatable on the stud. This plate is cut out or recessed to form an abutment 13, and a pair of hooked arms 14, 15, the ends of these hooked arms being arranged to project through the slots 7 of the plate 4, before referred to.

In the position shown in Fig. 5, the parts are shown in closed or latched position. 20 By rotating the plate the abutment 13 presses against the end of the leg 6 of plate 4 and pushes the plate outwardly to the position shown in Fig. 6, the hooks disengaging from the slots in the legs of the 25 plate. By positioning hooked arm 14 so that when it is projected through the slot 7 the hook is transverse to the direction of movement of the plate 4, the hook cannot be freed from the plate until the movable 30 plate is rotated. Any accidental opening of the bag is thus effectually prevented. While two hooked arms have been shown, and will preferably be used, arm 15 may be omitted, if desired, arm 14 being relied on 35 to hold the parts in position. In the construction illustrated, the closing of the bag causes the end of the leg 6 of the latch member to come in contact with abutment 13 and through it rotates the plate in the 40 opposite direction and brings the hooked arms into their holding position in the notches of the legs 5, 6 of the plate 4.

In accordance with the invention, there is provided an actuator for rotating the 45 plate whereby the latch is opened. The particular construction of this actuator may be somewhat varied. The actuator will, however, be so constructed as to be normally held out of operative turning relation with 50 the plate, so that, to turn the plate the actuator must first be brought into operative relation therewith and then given a further movement to rotate the plate. As illustrated, the actuator is in the form of a stud 16, having an inner recess 16' and provided with a finger grip 17 by which it may be rotated. The actuator may be mounted in the frame in any suitable manner. In the particular 55 construction illustrated the actuator is provided with two or more depending lugs or pins 18 which enter loosely in suitable holes or recesses 19 in the plate, the plate being rotated by the actuator through these pins. The accidental operation of the latch by 60 the actuator is prevented by normally hold-

ing the actuator out of turning relation with the plate so that the actuator must be released before it can be operated to move the plate. The construction for effecting this may be somewhat varied. As illustrated, 70 there is provided a pair of supports 20 on which is secured a cross plate 21, having a central aperture through which the actuator may project. This cross plate 21 intermediate the ends of each of its long 75 sides is notched at 22. On the actuator are transverse pins 23 which extend into the notches 22 when the actuator is in normal 80 position, the actuator through these pins being prevented from rotation until it has been depressed sufficiently to free the pins from the walls of the slot. This depression of the actuator is effected by pushing it downwardly, the pins 18 on the actuator 85 sliding in the holes 19 in the plate before referred to.

From the construction so far described, it is apparent that the bag cannot be accidentally opened and the latch is held closed until the actuator has been depressed and 90 then given a rotary movement to rotate the plate. In the best constructions, the actuator will be so constructed that when the bag is closed the closing movement of the latch returns the actuator to its normal 95 position, that is, the position in which it is in inoperative turning relation with the plate. The construction for effecting this may be somewhat varied, but a simple and convenient construction consists in seating 100 the actuator against a spring 25, this spring being conveniently located within the recess 16' in the stud 16 and taking against the plate. When the plate is rotated in a reverse direction, the actuator is likewise 105 rotated through pins 18 until pins 22 come opposite the slots in cross plate 21, when the spring will force the pins into the slots and the actuator is thus held against rotary movement until it is again depressed. 110

In Figs. 7 and 8, the principle of the invention has been shown as applied to an ordinary gas fixture used for gas lighting purposes. In such a construction it is desirable that the valve for controlling the 115 supply of gas to the burner be securely held against accidental displacement, and it is furthermore desirable that when the valve is operated to discontinue the supply of gas that the mechanism for thus holding 120 the valve should be returned to such position that the valve cannot be again operated until such mechanism has been actuated.

While the construction by which the invention may be utilized for this purpose 125 may be somewhat varied, in the construction illustrated in Figs. 7 and 8, the valve 30 of usual construction, is mounted to rotate on a stud 31. The lower end of this valve is provided with a key-way 32 in the form of 130

a narrow slot extending across the lower face of the valve. This valve is operated in accordance with the invention by an actuator, the particular construction of which 5 may be varied. The actuator will, however, be of such construction that it is normally out of operative or turning relation with the valve and before it can be operated to turn the valve must be brought into operative relation therewith. In the particular construction illustrated, the actuator includes a stud 33 which is adapted to work in a recessed hub 34 suitably secured in any manner to the fixture 35. The actuator is 10 provided with a handle 36 which may be grasped by the fingers to operate the actuator. The other end of the actuator is slotted and in the slot is securely fixed a key 37 proportioned to take in the key-way 32 in the valve before referred to. The key 37 is somewhat longer than the diameter of the recess in the hub in which the actuator operates, and the hub 34 is provided with a transverse slot 39 in which the key seats 15 when the parts are in non-operative position, this construction forming a convenient support for the actuator through the ends of the key contacting with the bottom wall of the slot as shown in Fig. 8.

20 It will be seen from this construction that the actuator must be first pushed upwardly to free the key 37 from the transverse slot 39, and permit the actuator to be turned. When the actuator is so moved the key 37 25 enters the key-way 32 in the valve, and the valve may then be given a turning movement to open the same. The valve is thus held through the construction described securely against accidental opening. In the 30 best constructions, when the valve is operated by the actuator to close the valve, the actuator will be returned to normal or non-operative position. While this may be accomplished by various ways, in the construction illustrated there is provided a spring 35 40 which seats between a collar 38 on the actuator and a shelf 42 in the hub 34, this spring acting to cause the actuator to return to its normal position. When the actuator 45 is operated to close the valve, as soon as the key comes opposite the slot 39 in the hub 34, the action of the spring forces the actuator outwardly and frees the key from the key-way. The key cannot be returned into the 50 key-way until the actuator has been pushed

inwardly to free the key from the slot 39 in the hub.

The invention has been shown and described in a simple and convenient form, and as applied to a latch construction, and 60 a valve construction. It will be understood that changes and variations may be made in the particular construction employed, and that the invention is capable of a wide range of uses, and that it is not to be restricted to 65 the particular construction shown and described, or to the particular uses referred to.

What is claimed is:—

1. In a device of the character described, the combination of a rotary locking member, a rotary actuator movable into and out of rotary actuating relation with the member and having a projection for engagement with the member for rotating it, a spring against which the actuator is moved into 70 rotary actuating relation with the member and which acts to throw the actuator out of such relation therewith, and means carried by the actuator for locking it in non-rotatable position when it is returned thereto 80 by the spring.

2. In a bag or similar article, the combination with the bag frames of fixed plate 4 having slotted legs 5, 6, rotary locking plate 8 having locking arms 14, 15 arranged 85 to project into the slots in the legs, and actuator 16 for rotating plate 8.

3. In a bag or similar article, the combination with the bag frames of fixed plate 4 having legs 5, 6, rotary locking plate 8 having 90 hooked arm 14 taking in a slot in leg 5, abutment 13 on plate 8 with which leg 6 contacts and actuator 16 for rotating plate 8.

4. In a bag or similar article, the combination with the bag frames of fixed plate 4 having slotted leg 6, rotary locking plate 8 having hooked arm 15 taking in the slot in leg 6, abutment 13 on plate 8 with which leg 6 contacts, and an actuator 16 for rotating plate 8.

100 In testimony whereof, we have hereunto set our hands in the presence of two subscribing witnesses.
